United States Patent Office

Des. 220,759
Patented May 18, 1971

220,759

BUILDING OR THE LIKE

William C. Renwick, Barrington, Ill., assignor to
Brunswick Corporation, Chicago, Ill.

Filed Apr. 8, 1970, Ser. No. 22,332

Term of patent 14 years

Int. Cl. D25—04

U.S. Cl. D13—1

fig. 4

fig. 5.

fig. 6.

fig. 7

FIG. 1 is a top perspective view of a building showing my now design, where the top, the front, and the right side are visible;

FIG. 2 is a front elevational view of the building shown in FIG. 1;

FIG. 3 is a left side elevational view of the building;

FIG. 4 is a rear elevational view of the building;

FIG. 5 is a fragmentary horizontal sectional view taken at about the line 5—5 of FIG. 2 showing the entrance;

FIG. 6 is a fragmentary vertical sectional view taken at about the line 6—6 of FIG. 2 showing offset portions of the front and side walls;

FIG. 7 is a fragmentary horizontal sectional view taken at about the line 7—7 of FIG. 2 showing the relief in the upper portion of the front and side walls;

FIG. 8 is a top perspective view of a modified form of the building showing the top, right and front sides;

FIG. 9 is a front elevational view of the building shown in FIG. 8;

FIG. 10 is a left side elevational view of the building shown in FIGS. 8 and 9;

The rear, the entrance, the offset wall portions and the vertical relief in the upper wall portions in the building of FIGS. 8, 9 and 10 correspond with similar features shown in FIGS. 4, 5, 6 and 7.

FIG. 11 is a top perspective view of another modified form of the building, showing the top, right and front sides;

FIG. 12 is a front elevational view of the building shown in FIG. 11;

FIG. 13 is a left side elevational view of the building shown in FIGS. 11 and 12;

The rear, the entrance, and the offset wall portions of the building shown in FIGS. 11, 12 and 13 correspond with similar features shown in FIGS. 4, 5 and 6.

I claim:

The ornamental design for a building or the like, substantially as shown and described.
